UNITED STATES PATENT OFFICE.

ALLYN B. McINTIRE, OF NEWTON, MASSACHUSETTS, ASSIGNOR TO PEPPERELL MANUFACTURING COMPANY, OF BIDDEFORD, MAINE.

DESIGN FOR WRAPPING PAPER.

Application filed November 30, 1925. Serial No. 15,580. Term of patent 14 years.

To all whom it may concern:

Be it known that I, ALLYN B. McINTIRE, a citizen of the United States of America, residing at Newton, in the county of Middlesex and State of Massachusetts, have invented a new, original, and ornamental Design for Wrapping Paper, of which the following is a specification, reference being had to the accompanying drawing, forming part thereof.

The figure is a plan view of a sheet of wrapping paper showing my new design, which in practice is repeated over the entire surface of the paper.

I claim:

The ornamental design for wrapping paper as shown.

ALLYN B. McINTIRE.
